DESIGN FOR A GAME BOARD

Carl Edgar Smith, Jr., Baltimore, Md.

Application November 20, 1939, Serial No. 88,381

Term of patent 3½ years

To all whom it may concern:

Be it known that I, Carl Edgar Smith, Jr., a citizen of the United States, residing at Baltimore, in the State of Maryland, have invented a new, original, and ornamental Design for a Game Board, of which the following is a specification, reference being had to the accompanying drawing, forming part thereof, in which the figure is a top plan view of a game board showing my new design. The lining of the drawing is for the purpose of clearly differentiating different sections of the board. The game board is of no substantial thickness.

I claim:

The ornamental design for a game board, substantially as shown and described.

CARL EDGAR SMITH, JR.
